UNITED STATES PATENT OFFICE.

HORACE G. DOOLITTLE, OF KNOXVILLE, IOWA.

WALL-PAPER PASTING AND FOLDING MACHINE.

Application filed June 19, 1919. Serial No. 305,322.

To all whom it may concern:

Be it known that HORACE G. DOOLITTLE, a citizen of the United States of America, residing at Knoxville, in the county of Marion and State of Iowa, has invented new and useful Improvements in Wall-Paper Pasting and Folding Machines, of which the following is a specification.

The general purpose of the invention is to provide a machine having means for holding a supply of wall paper in a continuous row, then advancing the paper through a paste applying apparatus and finally folding the paper in the usual layers or folds for convenient handling when placing the same on the wall. Further the machine makes provision for measuring the length of paper pasted and folded and it is still further provided with means which will permit the formation of the supply roll from the individual rolls, the ends of the individual rolls being matched and secured together by an adhesive paper tape in the formation of the supply roll. The folding of the paper is accomplished by means of a movable platform, this platform being mounted for reciprocating movement and the movement being accomplished by a crank handle which aside from being operatively connected to the table is also operatively connected to the pasting and advancing rolls by which the paper is conducted from the supply rolls to the table. Automatically operated clamping members are carried by the table or platform and these clamp and securely hold upon the table the different plates formed in the operation of the machine.

Aside from the general purpose above mentioned, the invention further contemplates provision for an apparatus of the kind stated which is comparatively simple in construction, durable and effective in operation and inexpensive to manufacture.

Other and further purposes appear in the following description wherein the invention is set forth in detail.

To the exact construction in which it is shown and described, the invention is not to be restricted. The applicant reserves the right to make such changes or alterations as the actual reduction to practice may suggest, in so far as such changes or alterations are compatible in spirit with the annexed claims.

The same numerals of reference design-

nate the same parts throughout the several figures of the drawings, wherein:

Figure 1 is a view in side elevation of the improved apparatus or machine.

Figure 2 is a central vertical longitudinal sectional view through the structure of Figure 1.

Figure 3 is a vertical transverse sectional view through the structure of Figure 1.

Figure 4 is a vertical sectional view taken on the line 4—4 of Figure 1.

Figure 5 is a top plan view of the structure of Figure 1.

Figure 6 is a sectional view taken through the driving sprockets of the apparatus taken on the lines of their diameters.

Figure 7 is a detail view partly in section and partly in elevation of the anti-friction roller and a portion of the crank arm forming part of the operative connection between the driving means for the table and the table itself.

Figure 8 is a detail perspective view of one end of the table.

Figure 9 is a detail elevational view of the registering or counting mechanism.

Figure 10 is a section on the line 10—10 of Figure 9.

As illustrated, the invention comprises a main frame 1 of open construction and provided at their end with transversely disposed bars 2 which are formed with openings 3. These bars are provided for the purpose of supporting a track for the work table which is moved backward and forward in the operation of the machine and this track comprises two spaced rails 4 which are made preferably of round rod and formed with right angular bends at their terminals, these right angularly bent portions passing through the bars 2 on their upper edges to have their extremities enter the openings 3 in which nuts 5 are carried, the latter threadingly engaging the right angularly bent portions and bearing against the outer sides of the opening 3, thus securing the two bars or rails 4 in position thereon, as is apparent in Figures 1, 2, 3 and 4 of the drawings.

The work table which travels on the tracks or rails 4 constitutes a platform 6 with depending side and end plates 7 and 8. On the under face of the platform 6 there are carried the pillar blocks 9 which are arranged

in pairs as shown in Figure 3, each pair supporting an axle 10 on which a peripheral grooved wheel or roller 11 is rotatably mounted. The platform 6 carries sufficient pillar blocks 9 to provide for four wheels or rollers 11, two adjacent one end and two adjacent the other, so that the platform may be moved backward and forward in the direction of the length of the frame 1.

5 10 Centrally disposed with reference to the platform 6 of the work table and depending from the bottom face thereof there is a plate 12, this plate being formed with a slot 13 in the direction of its length and 15 being secured at its upper end to the platform 6 by means of angles 14 attached both to the edge of the plate and to the underface of the platform by means of fasteners 15 which are preferably lag screws. This 20 plate 12 is the medium through which motion is transmitted to the work table and in order that it may be relieved from undue strain at its lower end, there are provided the diagonally disposed braces 16 which are 25 secured on opposite edges of the plate 12 adjacent its lower end and which are further secured to the underface of the platform adjacent its opposite ends.

30 The frame 1 of the machine on opposite sides and substantially at its longitudinal center carries the upright plates 17, between one of which and the plate 12 a standard 18 is provided. The standard 18 adjacent its upper end and the plate 17 next to it each 35 carry a bearing 19 in which the shaft 20 is journaled, this shaft 20 being formed with a crank portion 21 on the extremity of which there is loosely mounted a roller 22, this latter working in the slot 13 formed 40 in the plate 12. Obviously when the shaft 20 is turned, as it is in the operation of the machine, a corresponding angular movement is imparted to the crank 21 with the result that the roller 22 is caused to travel 45 up and down in the slot 13 as the crank rotates, thus performing moving the work table first in one direction and then in the other along the tracks or rails 4.

50 On the outer face of the plate 17 in which its bearing is carried, the shaft 20 carries a sprocket wheel 23 and a turning crank 24 attached to it outside of the sprocket wheel, there being trained over the sprocket wheel 23 a chain 25 which is also trained over a 55 sprocket wheel 26, this sprocket wheel 26 being rotatably mounted on a stud 27 carried in the plate 17 at a point a substantial distance above the shaft 20. In addition to the sprocket 26, the shaft 27 carries 60 a second sprocket 28 which is also rotatably mounted on the shaft. This sprocket 28, however, is provided with a turning crank 29 by which rotary movement may be readily imparted to it by hand. The sprocket 28 65 is designed for positive connection with the

sprocket 26 to the end that both may be rotated by means of the crank 29 but in some operations of the machine it is desirable to have the two sprockets turn independently of each other. To this end there 70 is carried by the sprocket 28 a pin 30 which passes axially through the sprocket and carries a head 31 on the outer face of the sprocket. This pin 30 is of sufficient length to enter a socket or hole 32 formed in the 75 sprocket 26 and in order that the pin may be normally retained in the socket 32, there is provided in surrounding relation to the pin a coil spring 33 which bears one end against a transversely disposed pin 34 80 carried by the pin 30 and the other end against the inner face of the sprocket 28. When the pin 30 engages the socket 32, a pin 35 carried by the head 31 seats in a socket prepared for it in the sprocket 28. 85 With the engagement of the pin 30 in the socket 32, the two sprockets 28 and 26 become positively connected so that any movement imparted to the one is immediately transmitted to the other. The construction 90 provides, however, for a disengagement of these two sprockets and this is accomplished by withdrawing the pin 30 from the socket 32 until the pin 35 is freed from its socket. A slight angular movement then imparted 95 to the head 31 will throw the pin 35 to a position where it may not enter its socket, but its end will bear against the outer face of the sprocket 28 and the pin 30 will be withdrawn from its socket 32 against the 100 pressure of the spring 33. The two sprockets 28 and 26 may then be readily operated independent of each other.

The crank 29 being the general operating medium of the machine, the sprocket 26 105 serves as a means for transmitting the motion of this turning crank to the work table operating mechanism but the sprocket 28 serves as a medium for transmitting the movement of the crank to the paper pasting 110 and feeding apparatus described herein-after.

A suitable reservoir 36 for paste is provided and is supported between the two plates 17 at their upper ends, the cover 37 115 of the said reservoir carrying at its center a vertically disposed thimble or sleeve 38 which is internally threaded to receive the screw stud 39 which is formed with a head 40 to permit its being readily turned for the 120 purpose of elevating or lowering the screw stud. The paste reservoir 36 is formed with bottom and side walls which in cross section present the segment of a circle and the bottom at the lowest point is formed with a 125 plurality of longitudinal perforations 41 through which paste may leave the reservoir. The shaping of the bottom and side walls of the reservoir, as shown, makes for the 130 direction of the paste to these perforations

and thus provides for practically utilizing all the paste contained in the reservoir, since the contents of the latter will always float toward the lowest point and it is at this point that the perforations 41 are formed.

Of course it becomes essential to provide some means to prevent paste leaving the reservoir when the device is not in use and to this end there is disposed within the reservoir a bar 42 which may be forced down into contact with the bottom of the reservoir or elevated from contact therewith. This bar at its center has a pivotal connection with the lower end of the screw stud 39 and if the latter is turned to lower, the bar is forced brought into firm contact with the bottom of the reservoir when it effectually closes the perforations 41. When turned in a direction to elevate it, the bar is forced elevated and being raised clear of the bottom the paste may flow under it and through the perforations.

Rotatably mounted directly below the reservoir 36 so that it may receive paste flowing through the perforations 41 thereof, there is a feed roll 43 which is carried on an appropriate shaft one end of which projects far enough through that plate 17 in which the shaft 27 is mounted to permit its being equipped with a gear 44, this gear being in mesh with a gear 45 carried on the shaft of a roller 46 which is similar to the roller 43 but which receives the paste from the roller 43 for transfer to the wall paper which is passed between this roll 46 and a roll 47, the latter being of similar construction to the roll 46 but acting to hold the wall paper in close contact with the roll 46 so that the paste received from the roll 43 may be transferred to the back of the paper. The roll 43 is substantially a distributing roll. The paste reaching the roll 43 through the perforations 41, is not distributed over the surface of the latter but forms in rings there-around until it reaches the roll 46, the contacting surfaces of the two rolls then serving to distribute the paste over them and the latter rolls transfer this paste to the wall paper paste between it and the roll 47. The roll receives its rotary motion by an operative connection with the roll 46, this operative connection being in the form of a gear 48 meshing with the gear 45. The gear 48 is built with a bevel gear 49 on the inner side thereof, this bevel gear 49 facing the adjacent plate 17 and meshing with a bevel gear 50 carried at the end of a shaft 51 which is disposed in a horizontal plane and in the direction of the length of the machine. This shaft 51 constitutes the operating medium for a register or counting mechanism to indicate the length of paper passed through the machine in the operation thereof. The shaft is journaled in two vertically disposed

blocks 52 which are interconnected by means of rods 53, of which there are two, one disposed above and the other below the shaft. These blocks carry at their upper end a plate 54 on which are inscribed suitable indicia designed to indicate in linear units the length of paper passed over the roll 47. The two blocks 52 and rods constitute a frame which is attached to that plate 17 on that side of the machine where the driving gears are carried and this frame is attached to the plate by having one of its blocks 52 secured thereto in any suitable manner.

The shaft 51, between the two blocks in which it is journaled, is provided with screw threads, as indicated by 55, and a movable counting medium is slidably mounted on the rods 53 and provided with a threaded hole in which the threads 55 of the shaft 51 engage. This counting medium consists of the complementary blocks 56 and the bearing holes for the rods 53 and the threaded hole for the threads 55 are formed half in one block and half in the other, the two blocks being detachably connected together by means of a screw 57 which passes loosely through one block and threadingly engages the other. Obviously when the screw 57 is tightened to secure the two blocks 56 firmly together, the turning of the shaft 51 will by means of its screw threads 55 cause the counting medium to be advanced from one end of the counter frame to the other end, when the pointer 58 which is formed with one of the blocks will read across the indicia on the plate 54, thus indicating the length of paper passing over the roll 47. The counting mechanism is directly connected to the roll 47 and it is of course so constructed and its operating parts so proportioned that the movement of the pointer 58 over certain indicia on the scale on the plate 54 will indicate the passage of a specified length of paper over the roll 47.

Directly below the roll 47 there is mounted a trimming couple for the purpose of removing the selvage edges from the wall paper and this trimming couple consists of the rolls 59 and 60, each of these rolls carrying a circular knife 61 adjacent one end and being formed against the other end with a peripheral groove 62. It will be observed that the knife carried by the one roll plays within the groove formed in the other roll. The two knives are therefore carried adjacent the opposite ends of their respective rolls.

These two rolls 59 and 60 are carried on suitable shafts both of which are rotatably mounted in the plates 17 and operatively connected by means of intermeshing gears 63. The shaft of the roll 59 protrudes a sufficient distance beyond its gear 63 to receive a sprocket 64. Movement is imparted to the roll 59 through the sprocket 64 and

the operative connection between the two rolls consisting of the gear couple 63 makes for the imparting of motion to the roll 60. The rolls 43, 46 and 47 being operatively connected by means of their attendant gears 44, 45 and 48, the imparting of a rotary movement to the one will serve to set all three in motion. The shaft of the roll 46 is therefore extended beyond the gear 45 and carries on this extended end a sprocket 65 over which a chain 66 is trained, this chain passing also over the sprocket 64 and around the sprocket wheel 28. It is apparent from this construction that the turning of the sprocket wheel 28 by means of its crank handle 29 will serve to put the trimming rolls as well as the feeding and pasting rolls in motion.

To provide an adequate supply of paper for the operation of the machine, it is intended that a supply roll shall be formed by joining end to end a number of the usual rolls. To this end there is provided on the frame 1 on either side thereof and adjacent to the plate 17 on that side, a second plate or standard 67, these two standards at their upper ends being formed with slots 68 in which a rod 69 may be supported so that it may be readily removed when desired. This rod 69 is intended as a support for a supply roll, such as the supply roll 70 indicated in the drawings. This supply roll 70 consists of a number of the usual rolls whose ends have been previously matched and connected together, provision being made for effecting this in a quick and easy manner, as is explained hereinafter. The two standards 67 aside from supporting the supply roll, also support a horizontally disposed plate 71, the level of the upper face of which is approximately the same as the level of the lower side of the roll 46. This plate acts as a support for the paper between the point where it leaves the supply roll and enters between the rolls 46 and 47. The two side plates 72 are carried at the ends of the plate 71 and serve as guides for the side edges of the paper, thus ensuring it maintaining a certain position when passing between the rolls.

Below the roll 60 a transversely disposed plate 73 is carried, this plate being attached to the two plates 17 with its width disposed in a vertical plane. Below this plate 73 there are carried two transversely disposed bars 74, the two being spaced from each other and positioned one below the roll 60 and the other below the roll 59. The paper leaving the trimming rolls 59 and 60 passes before the plate 73 and between the two bars 74, being laid in folds upon the work table as the latter is advanced to and from along its track.

A clamp is provided adjacent each end 65 of the work table for securing the folds of

paper in place thereon as the paper is folded and each of these clamps comprises a pair of bell crank levers 75 secured together in spaced relation to each other by pins 76. These clamping feet or levers 75 are pivotally mounted on the work table, each pair between a pair of upstanding ears 77 which are attached to the work table. Connected with each pair of levers 75 there is a contractile spring 78 which is attached one end 75 to one of the pins 76 and the other end to the upper face of the work table, this pin being positioned adjacent the extremity of one arm of each of the levers. The spring serves normally to hold the ends of the other arms of the bell crank levers in contact with a block 79 mounted on the upper face of the work table. The separate folds of paper, when the machine is being operated, are held on the work table by these clamping members and in order that each fold may be clamped down in turn, it is necessary to provide means for raising the clamping members at certain times during the operation of the machine. To this end there are provided lifting arms 80 one of which is mounted on each bar 74 and disposed to project in the direction of one of the clamping members whose pin 76 to which the spring 78 is connected, is provided with an extension 81 95 projecting laterally from the side of the clamping member. The lifting arm 80 is shaped so that as the clamping member advances toward it the extension 81 which projects laterally from the side of the clamping member may ride up on the arm, thus raising the clamping member. Each clamping member is raised to permit a fold of paper to be placed thereunder at the time its end of the work table is brought to the longitudinal center of the main frame 1.

In addition to the clamping members, there are provided transversely disposed fingers for engaging and assisting in the formation of the folds of paper. These transversely disposed fingers are formed preferably each from a single piece of wire or rod and have a vertically disposed portion 83 in which there is formed a loop-like crank portion 84. This wire or rod is pivotally mounted on the work table, the vertically disposed portion 83 passing through a pair of spaced bars 85 between which the crank portion 84 stands. This crank portion 84 precludes longitudinal movement 110 of the vertical portion 83 but will permit pivotal movement thereof. A right angularly disposed portion 86 constituted the fold engaging finger and projects over the top of the work table, being normally disposed in the direction of the width of the latter. The fold engaging finger 86 is designed to move in either direction on the pivot point of the vertically disposed portion 83 the crank portion 84 being disposed in a 125

plane at right angles to the plane of the finger 86 and a tension spring 87 being attached between this crank portion 84 and a plate 88 spanning the bars 85. The spring 87, by means of this construction, provides for keeping the finger 86 normally disposed in the direction of the width of the work table and obviously the swinging of the finger in either direction will be against the 10 tension of this spring.

The work table carries four of these fold engaging fingers 86, two adjacent each end disposed on opposite sides of the work table and projecting towards each other. Means 15 are provided for swinging the fingers backwardly with respect to the directions of movement of the work table when the latter reaches the extremity of its movement in either direction. These means are carried 20 by the frame 1 and consist of the L-shaped arms 89 and 90 which are attached to the frame so that one leg of each lies in a horizontal plane with the other depending in a vertical plane. The fingers 86 may pass 25 under the horizontal portions of these arms but are engaged by the depending or vertical portions and if the table be advanced to one end of the frame, the fingers 86 at the forward end of the table will be engaged 30 by the depending portions of the arms 89 at that end of the frame toward which the table is advancing and these fingers will therefore be swung back in the direction of the length of the table. Simultaneously with 35 this the fingers carried at the rear end of the advancing table will be engaged by the depending portions of the arms 90 and swung in the same relative directions in which the forward fingers 86 are swung. 40 If paper is being passed from the trimming rolls 59 and 60 to the work table and laid in folds upon the latter as the table is moved backward and forward, the paper will pass down between the bars 74 and to 45 the left, as viewed in Figure 2, to be held under the clamp thereof. Presume the work table to be moving toward the left as viewed in Figure 2 and the clamp to have engaged a fold in the paper. As the work table 50 moves toward the left the paper is drawn off the supply roll by the moving table through the instrumentality of its clamping levers 75 and fingers 86 which engage between the two layers of the fold. When 55 the table has reached the extremity of its movement in this direction, the L-shaped arms 89 on the left hand end of the machine will engage the fingers 86 on the left hand end of the work table, swinging them 60 back in a right hand direction until they are nearly disposed in the direction of the length of the work table, thus withdrawing them from between the fold which they previously engaged. Simultaneously with 65 this the fingers 86 at the right hand end of

the work table will be swung in the same relative direction by the arms 90 which swing these fingers to a position in the direction of the length of the work table, thus permitting these fingers on the right hand 70 end of the work table to pass that portion of the paper passing between the bars 74. These fingers will therefore be moved to a position where they may engage behind that part of the paper passing between the bars 74 down to the work table. The table having reached the extremity of its movement in the left hand direction and started on its return movement—that is, when it starts its reverse movement which right handedly as viewed in Fig. 2—all four fingers will be moved away from the arms which they previously engaged and will be caused by their attendant springs to assume their normal positions, the fingers at the 80 right hand end of the work table swinging back to a transverse position on top of the fold which they previously engaged and the fingers at the right hand end of the work table passing in behind that portion of the 85 paper passing down between the bars 74 to the work table. The fingers on the right hand end of the table will therefore engage the paper and as the table advances in a right hand direction will create a pull upon 90 the paper and form another fold.

As the table advances to its extreme right hand position, as above described, the lifting arm 80 on the right hand bar 74 will engage the extension 81 of the pin 76 of the right hand clamping members. These clamping members will therefore be raised from contact with their attendant block 79 and the fold being formed by the fingers on the right hand of the table as the latter starts 100 backward will be laid upon the block. After the table has advanced far enough in its return movement to release the extension 81 from the lifting arm, the spring 79 will draw the clamping members down upon the fold 105 and it will be held in place thereon until the table reaches the end of its right hand movement, when the same cycle of operations will be repeated for the forming of a new fold when the table starts forward again in 110 a left hand direction.

To provide for the convenient forming of the supply roller 70, the main frame 1 is provided with a top plate 91 to whose edge there is hingedly attached a swinging leaf 115 92. This swinging leaf may be turned upward, when not in use, as indicated in Fig. 1 of the drawings, but during the operation of the machine it is swung outwardly to lie in the same plane as the top plate 91 and in order that it may be maintained in this plane, there is provided a swinging brace member 93 which is hingedly attached to the frame 1 adjacent the bottom of the latter. This brace member at its upper edge engages 120

a transversely disposed batten 94 mounted on the under face of the swinging leaf 92. At the outer edge of the swinging leaf and on the top face of the latter there are carried two upstanding supports 95, reset from their upper edge, as indicated at 96, to permit a bar 97 being held by the supports. Obviously this bar may be readily removed or placed in position on the supports and its purpose is to hold the usual roll of wall paper, such as that indicated by 98. The rod 97 is inserted through the roll of paper and then placed upon the supports. The paper is thereupon transferred from this roll 98 to the roll 70, or if the roll 98 be the initial roll, it is transferred directly to the rod 69, it being wound around the latter and off the rod 97. When one roll 98 has thus been wound around the rod 69 the beginning of this roll matches with the end of the roll previously wound around the rod 69. To provide for securing the two rolls together when matched in this manner, the roll 99 of sealing tape is provided, this sealing tape being wound in a roll with its adhesive face outward. This roll of tape 99 is carried on a spool 100 which in turn is carried by a small shaft 101 rotatably mounted in depending bearing supports 102 which are attached to the under face of the swinging leaf 92. The tape, therefore, may be drawn off the roll 99 and across the top face of the leaf 92. The two matched ends of the two rolls being connected are thereupon laid down upon the tape and the paper moistened, this operation causing the tape to adhere the two connected ends for the purpose of holding them together. When this has been accomplished the second roll may be wound off the roll 97, whereupon a third roll is wound upon the roll 97 and the previous operation continued until a supply roll, such as the supply roll 70, is obtained, this supply roll by the operation cited above, being composed of a number of the usual rolls such as the roll 98.

Paper from the roll 70 is fed between the feed rolls 46 and 47, the latter of which acts as a drying roll and the former as a pasting roll, the roll 43 receiving paste from the reservoir 36—after the bar 42 has been raised—and communicating this to the roll 46 over which it is distributed and applied to the paper. From the feed rolls consisting of the distributing roll and the drying roll the paper passes between the trimming rolls 59 and 60 whose knives 61 serve to trim the selvage edge therefrom. The paper is then passed on to the table on which it is folded in the manner before described.

Obviously the means for operatively connecting the sprockets 28 and 26 provides for operating the table independently or the feed and trimming rolls independently of the table. All that is necessary to accom-

plish this is to withdraw the pin 30 from the eye formed for it in the sprocket 26. The crank 29 will then, when turned, rotate only the feed and trimming roll. Thus the paper may be initially brought to the work table without the latter being reciprocated during such operation. If it is necessary to move the work table without moving the feed and trimming rolls, this can be accomplished by the simple turning of the crank 24. When the pin 30 is engaged with its eye or socket 32 formed in the gear 26, the crank 29 serves to move all of the parts of the device.

The invention having been described, what is claimed as new and useful is:

1. A machine of the character described embodying a work table, means for reciprocating the work table, means for feeding paper from a supply roll to the work table, paper folding means carried by the work table, a clamp comprising spaced bell crank levers, pins spanning the levers and securing them together, means for pivotally mounting the levers on the work table, a contractile spring disposed between the levers and tensioned between one of said pins and a point on the work table, one of said levers being provided with lateral extension, and a relatively fixed lifting arm disposed in the direction of the length of the table, and engaging said extension to raise the levers against the tension of the spring in one position of the work table.

2. A device for the purpose indicated comprising a main frame, rails carried by the main frame, a roller supporting working table traversing the rails and rotary crank shaft operatively carried with the work table to impart reciprocatory movement to the latter upon rotation of the shaft, a sprocket wheel carried by said crank shaft, a stud carried by the main frame in parallelism with said shaft, a sprocket wheel rotatably mounted on the stud, a chain traversing the last said sprocket wheel and that on the crank shaft, paper feeding rolls carried by the main frame and operatively connected for movement in synchronism, a second sprocket wheel carried on said stud, sprocket wheels operatively connected with said rolls, a chain traversing the last said sprocket wheels and the second sprocket wheel mounted on said stud, a crank handle connected with the last said sprocket wheel, and a spring actuated pin carried by the same and engageable with and disengageable from the first said sprocket wheel carried on the stud for operatively connecting the two sprocket wheels for rotation in unit or separately.

3. A machine for the purpose indicated comprising a main frame, a table slidably mounted in the main frame and provided with means for reciprocating the same, means for feeding paper from a supply roll

- to the table, spaced bars carried by the table and extending longitudinally of the latter, fold engaging fingers of angular construction and having one leg pivotally mounted 5 in said bars and formed with a crank portion disposed between said bars, the other legs being disposed normally transversely of the work table at which time the crank portions are disposed longitudinally thereof, and a spring tensioned between the crank 10 portion and points on the table to dispose the fingers normally transversely of the table but permit of them yieldingly moving in either direction toward positions in the direction 15 of the length of the table.
4. A machine for the purpose indicated comprising a main frame, a table slidably mounted in the main frame and provided with means for reciprocating the same, means 20 for feeding paper from a supply roll to the table, spaced bars carried by the table and extending longitudinally of the latter, fold engaging fingers of angular construction and having one leg pivotally mounted in
- said bars and formed with a crank portion 25 disposed between said bars, the other legs being disposed normally transversely of the work table at which time the crank portions are disposed longitudinally thereof, and a spring tensioned between the crank 30 portion and points on the table to dispose the fingers normally transversely of the table but permit of them yieldingly moving in either direction toward positions in the direction of the length of the table, the 35 frame being provided with L-shaped arms disposed at points co-incident with the points of extreme movement of the table in opposite direction for engagement with the fold engaging fingers at the adjacent ends 40 of the table, the frame being further provided with intermediately positioned L-shaped arms for alternate engagement with the fingers at the opposite ends of the table.
- In testimony whereof he affixes his sig- 45 nature.

HORACE G. DOOLITTLE.
